UNITED STATES PATENT OFFICE.

PETER J. SEHN, ALBERT P. SEHN, AND EDWARD J. SEHN, OF JOHNSTOWN, PENNSYLVANIA.

SPLICE BAR FOR RAILS.

Application filed July 21, 1927. Serial No. 207,496.

This invention relates to improvements in splice bar constructions for holding rail sections together.

The primary object of the invention is the provision of an improved splice connection for rail sections, by means of which the adjacent ends of the said rail sections will be efficiently maintained in flush aligning relation and thus eliminating low joints. 10 A further object of this invention is the provision of an improved splice arrangement for rail sections, which may be efficiently attached by means of unskilled labor, in such relation that splice connections for 15 the rail sections may be very readily disconnected, without mutilation of parts to any extent.

A further object of this invention is the provision of an improved splice connection 20 for rail sections, which is of such nature as to keep down maintenance expense in so far as rail placement is concerned, and which will also cut down upkeep on repairs of rolling stock, by reason of maintaining the rail sections in true alignment, so that the rolling stock may ride much easier than with usual rails embodying conventional splice connections.

Other objects and advantages of this invention will be apparent during the course 30 of the following detailed description.

In the accompanying drawings, forming a part of this specification, and wherein similar reference characters designate corresponding parts throughout the several views,

Figure 1 is a fragmentary side elevation of the improved splice connection for rail sections, showing certain parts in section.

Figure 2 is a transverse sectional view 40 taken substantially on the line 2—2 of Figure 1, looking at the splice connections from an end thereof.

Figure 3 is a sectional view taken longitudinally of the splice bar connection for 45 rail sections substantially on the line 3—3 of Figure 1.

Figure 4 is a fragmentary perspective view of details of a splice bar of the improved splice connection.

50 Figure 5 is a longitudinal sectional view taken through certain wedge connections of the splice construction, showing their relation with respect to the rail sections, for permitting expansion and contraction of the latter.

Figure 6 is a transverse sectional view through a rail, showing the assemblage relation of splice bars with respect to the rail and with respect to a rail foot plate.

Figure 7 is a transverse sectional view 60 taken substantially on the line 7—7 of Figure 3, showing the relative construction of parts of the improved splice construction, at a wedge connection thereof.

Figure 8 is a perspective view of wedge 65 parts of a novel wedge construction for the splice arrangement.

Figures 9 and 10 are transverse sectional views taken substantially on their respective lines in Figure 7 of the drawings. 70

In the drawings, wherein for the purpose of illustration is shown but a preferred embodiment of this invention, the letter A may generally designate the improved splice construction for rail joints, for the holding 75 of rail sections B and C in a connected jointed alignment. The improved splice construction A includes the splice bars D and E, at opposite sides of the rail sections B and C, having a plurality of improved 80 devices F, preferably of a wedging nature, transversely extending through the rail sections B and C to maintain the splice bars D and E in assembled relation for connecting the rail sections B and C; the improved 85 splice construction A furthermore including a foot plate G in a cooperative rail connecting and aligning association with the splice bars D and E and the rail sections B and C.

The rail sections B and C are of the usual 90 construction, including the reduced web portion 20, on the top of which the rail ball or head 21 is formed, with base flanges 22 and 23 therebelow, of conventional standard cross section. In the splice connected webs 95 of the rails B and C, it is preferred to provide round or circular openings 25, in any approved number, although it is thought that but two of said openings 25 will be sufficient for each rail section B and C. 100

The foot plate G includes a plate body 27^a, on which the rail flanges 22 and 23 rest, the same providing a flat top surface 28^a for receiving the flat bottom surface of the rail sections B and C, as illustrated in the drawings. At the outer longitudinal margins of the rail foot G, it is preferred to provide integral upwardly converging flanges 27 and 28, overhanging the rail surface 28^a of the foot body 27^a, in such a relation that 110

the rail flanges may be freely slipped into the spaces between the flanges 27 and 28 and the foot body 27^a. In fact, while the outer edges of the rail flanges 22 and 23 slide 5 against the junctures of the foot flanges 27 and 28 of the foot body 27^a, above the flanges 22 and 23 there is sufficient space to permit easy sliding of the rail sections into place in the foot G, as can readily be understood. 10 The foot flanges 27 and 28 converge upwardly in such relation that when the rail flanges are received therein there will be spaces 30 and 31 provided beneath the flanges 27 and 28 respectively and the top 15 surfaces of the rail base flanges 22 and 23, as is illustrated in Figures 2, 6 and 7 of the drawings. The rail foot flanges 27 and 28 do not extend to the web 20 of the rail, but there is sufficient space between the upper 20 free edges of the foot flanges 27 and 28 and the facing sides of the web 20, to receive the splice bars D and E, in a relation to be subsequently described.

The splice bars D and E are of the same 25 construction, each including a preferably flat elongated body 40, which at the inner surface thereof is grooved at 41, so that only the upper and lower longitudinal portions of the inner side of the splice bar may abut 30 against the facing surface of the rail web 20, as is apparent from Figure 7 of the drawings, and in the usual construction for splice bars. The upper edges of the splice bars D and E, slope downwardly at 44 from 35 the outer sides 45 of said splice bars to the inner sides thereof, adapted to fit into a conforming abutting engagement with the under sloping surface 45 of the rail ball 21. At the lower longitudinal margins of the 40 splice bars D and E, each of the same is preferably provided with a wedge foot 46, extending transversely to the plane of the respective splice bar, beyond the outer side 45 of said splice bar. These wedge feet 46 for the splice bars D and E, have upper surfaces 47, located in a transverse plane with respect to the plane of the outer side 45 of the splice bar, and in an angular relation with respect to the splice bar outer side 45, of greater than 90°. The lower surface 49 of the splice bar foot 46 is located preferably nearly parallel to the surface 47, for the major width of the splice bar flange 46, and towards the outer edge the surface 50 of 55 the splice bar flange or foot 46 is in obtuse angular relation with respect to the surface 49, inclining to an intersecting relation with the surface 47 to provide a chisel edge 51, at the free end or edge of the said splice bar 60 foot or flange 46.

Each of the splice bars D and E is provided transversely therethrough with a plurality of openings, preferably four in number, two of which openings are adapted to 65 receive the connecting devices F for each rail

section B and C. These openings, illustrated at 55 throughout the drawings, are of an unusual shape, preferably including four flat sides, in the form of a square, with fillets at the juncture of the flat sides, so that the openings 55 have a substantially polygonal shaped appearance; the intention being to provide an opening 55 having at least one, and preferably four flat sides, against which an abutting flat side of the wedge 75 device F is adapted to engage, to prevent relative rotation of the latter in the opening of the wedge plates, and to insure of the absolutely guided wedge movement of the wedge devices F with respect to the rail and 80 splice bars.

Longitudinally at the outer side of each of the splice bars D and E, it is preferred to provide a recess, on a line above the opening 55, the recess providing a sloping surface 60 inclined from the plane of the outer face of the splice bar inwardly towards the openings 55 and terminating in intersecting relation with said openings 55; it being intended that certain wedge surfaces of the wedge devices 85 F shall operate against the sloping surfaces 60, in a relation to be subsequently described.

As to the wedge construction F, the same includes a main wedge body 65, and a wedge key 66, which are cooperative and complementary, for fitting transversely through aligning openings 55 of the splice bars D and E and through an opening 25 of the rail web 20.

The main wedge body 65 at the ends thereof is provided with transverse right angled preferably upstanding lugs 67 and 68, the lug 68 having a convex top surface 70^a, in order to permit the entry of the wedge key 105 66 from the lug end 68 thru the openings of the rail and splice bars. The lug 67 on the other end is of polygonal formation, having flat side and top surfaces and is thus distinguished from the lug end 68. The body 65 between the lugs 67 and 68 is provided with an intermediate portion 70, having a convex surface which is complementary with an intermediate portion 71 of the wedge key 66, in providing a cylinder. Between the intermediate portion 70 and the lugs 67 and 68 are respectively provided portions 73 and 74, adapted to seat in the openings 55 of the splice bars D and E, whereas the intermediate portion is adapted to seat in the rail web opening 25. The portions 73 and 74 have top and side flat surfaces adapted to engage in abutting relation against the top and side flat surfaces of the splice bar openings 55, as can readily be understood 115 from Figures 9 and 10 of the drawings, to prevent relative rotation of the wedge device F in the splice bars. The sloping surface 75 at the bottom of the wedge body 65, slopes from the lug end 68 downwardly to 120

the lug end 67, so that the part 65 increases in thickness therealong from the lug end 68 to the lug end 67.

The wedge key 66 is complementary with the wedge body 65, as above mentioned, the wedge key 66 being relatively longer than the wedge body 65, and having the portion 71 which provides a lower convex surface for fitting in the circular opening 25 of the rail web 20, and the ends of the said wedge key 66 beyond this portion at the opposite sides of this portion 71 have lower and side flat surfaces of a nature to fit in abutment against the flat surfaces of openings 55 in the relation illustrated in Figures 9 and 10 of the drawings. It is to be noted that the top surface 80 of the wedge key 66 is flat throughout the length of the wedge key 66, being adaptable for sliding engagement on the sloping bottom surface 75 of the wedge body 65.

Referring to an application of the splice construction with respect to the rail sections B and C, the foot plate G is assembled on the rail sections B and C, to hold them in alignment, with the retaining flanges 27 and 28 overhanging the base flanges of the rails, as illustrated in the drawings. In this position the splice bars D and E are then applied across the joint, at opposite sides of said rail sections B and C, first in the position illustrated in Figure 6, showing that the feet 46 having a sort of hinge or wedge action at the free edges of the retaining flanges 27 and 28, with the said splice bar flanges 46 entering the spaces 30 and 31 between the retaining flanges 27 and 28 and the tops of the rail flanges 22 and 23. It is readily apparent that incident to the tapered edges of the flanges 46, the same may be readily assembled into the spaces 30 and 31, as illustrated in Figures 6 and 7, and upon forced movement the splice bars D and E may be moved with their inner sides against the opposite sides of the rail webs 20, and in this position of parts the top surfaces of the splice bar feet or flanges 46 rest in abutting engagement with the under surfaces of the retaining flanges 27 and 28, the bottom surfaces 49 of the splice bars D and E abut upon the top surfaces of the rail base flanges 22 and 23, and the sloping top surfaces 44 of the splice bars engage in abutting relation with the under surfaces of the rail ball 21. In this position of parts the wedging of the flanges 46 of the splice bars of course force the rail bases firmly into the bottom of the seat G, and as the splice bars are held against vertical movement between the rail base flanges and the ball of the rail, there can be absolutely no relative movement vertically of any parts of the connected splice construction on the rails. Either during this assemblage of the parts, or after the splice bars have been assembled to the above

positions, the sections 65 and 66 of the wedge construction F are then placed in aligning openings 55 and 25 of the splice bar and rail web respectively. The wedge body 65 of the wedge construction F is first assembled by 70 entering the rounded lug end 68 thereof thru the aligning openings 55 and 25, until the lugs 67 and 68 are at opposite sides of the splice bars D and E. From the opposite side the wedge key 66 is inserted beneath the wedge body 65, thru the aligning openings 55 and 25, and driven into place beneath the wedge body 65, forcing the latter upwardly until the lugs 67 and 68 ride on their tapered relatively upwardly diverging facing surfaces 80, against the sloping surfaces 60 at the outer sides of the splice bars; the riding upwardly of the surfaces 80 of the wedge lugs 67 and 68 against the upwardly diverging surfaces 60 of the splice bars D 85 and E, causes a wedge movement on the splice bars D and E, causing them to move together into a firmly seating relation against the web 20 of the rail sections, and in the positions above described, and illustrated in 90 Figure 7.

When the wedge key 66 has been firmly driven into place, it is to be noted that the pointed tapered end 85 thereof projects beyond the outer surface of the lug end 67 of the respective wedge body 65, and since it is preferred that the end 85 may bend without fracturing, the same is then bent transversely to the axis of the clamping construction F, against the outer surface of the lug 100 67, to hold the wedge 66 in position, against loosening, as can readily be understood from the drawings.

In the above described assembled relation of the parts of the wedge construction F, 105 it is to be noted that the intermediate portions 70 and 71 of the wedge body and wedge key 65 and 66 respectively lie in the web opening 25 of the rail section, but the portions of the wedge parts 65 and 66 which enter the splice bar openings 55 seat in snug abutment therein, in a keyed non-rotatable relation, as can readily be understood from Figures 9 and 10 of the drawings.

The fact that the openings 25 in the rail section web 20 are considerably larger than the cross sectional diameter of the wedge construction F entering the openings 25, enables longitudinal expansion and contraction of the rail sections B and C. In Figure 5 is illustrated the position of the rail sections B and C during a longitudinal contracted position of said rail sections, so that a space 90 is provided between the facing ends of the rail sections at the splice connection thereof, and it is readily apparent that the rail sections B and C may expand longitudinally from the position of parts illustrated in Figure 5, without strain on the wedge or bolt construction F, due to the loose fitting 115 120 125 130

thereof in the openings 25, which provides proper clearance for the closing of the joint space 90 when the sections expand longitudinally.

5 From the foregoing description of this invention it is apparent that a novel splice construction for rail sections has been provided, embodying features that will maintain the rails in a permanent and efficient alignment against liability of sag or loose fitting, thus increasing the safety factor and reducing maintenance expenses.

10 Various changes in the shape, size, and arrangement of parts may be made in the 15 form of invention herein shown and described, without departing from the spirit of the invention or the scope of the claims.

We claim:

20 1. In combination with rail sections each including a ball head, a web, and lateral base flanges, a shoe including a body plate on which the rail base flanges are adapted to seat, said shoe including retaining flanges overhanging the body plate in spaced relation to receive therebeneath the rail base flanges so as to provide spaces at opposite sides of the rail between the rail base flanges and the under surfaces of said overhanging shoe flanges, a pair of splice bars, one of 25 each at opposite sides of the rail web, each splice bar including a bar body for fitting against the rail web and of a height to wedge at the top and bottom edges thereof under the ball head of the rail and on the top surface of the base flange, said splice bars including lower transverse feet extending partially into the spaces and in wedging relation between the free marginal portions of the retaining flanges of the rail receiving shoe 30 and the rail base flanges, said splice bars and rail web having transverse aligning openings therein, and means extending through 35 said openings and abutting at the opposite sides of the splice bars for holding the splice bars firmly clamped in position against the 40 opposite sides of said rail web and between the ball head and base flanges of said rail.

45 2. As an article of manufacture a splice bar including a body plate provided with transverse openings therethrough, said body plate longitudinally at the lower edge thereof having a transverse foot extending beyond the plane of the outer surface thereof, said foot having faces in acute angular relation tapering to an edge located above the 50 bottom of the foot.

55 3. As an article of manufacture a splice bar for connecting rail sections comprising a splice bar body having transverse openings therethrough, said splice body at the outer side thereof being grooved to provide a sloping surface acute to the plane of the outer side, inclining from the outer side towards the inner side to an intersecting relation with said openings.

4. In a splice bar construction for rail joints the combination of a pair of splice bars having aligning openings therein, and wedge means extending through said aligning openings for holding the splice bars together 70 against relative movement away from each other.

5. In a splice bar construction the combination with a rail having a web provided with openings therethrough, splice bars at 75 opposite sides of the rail web having openings therethrough, in aligning relation with the openings of the rail web, and connecting members for holding the splice bars on the rail including relatively movable wedge 80 members seated in said aligning openings.

6. In combination with rail sections having openings through the webs thereof, splice bars having openings therethrough disposed at opposite sides of the rail web 85 and the openings thereof in aligning relation with the web openings, and wedge constructions assembled in said aligning openings of the splice bars and web, said wedge constructions including a main portion and 90 a key portion having abutting sliding surfaces inclined in acute angular relation with respect to the axes of said aligning openings, said wedge body having transverse lugs thereon for engaging the outer surfaces of 95 said splice bars when the key member of said splice construction is driven to a forced fit in the aligning openings against said wedge body.

7. In a splice bar construction for rails 100 the combination of a rail having a web with an opening therethrough, splice bars at opposite sides of the rail web having openings aligning with the opening of the rail web, a member extending through said aligning 105 openings of the splice bars and rail web, said member having transverse lugs on the outer ends thereof abutting against the outer surfaces of the splice bars, and wedge means cooperating with said member in said openings for forcing the lugs into firm abutment with the outer sides of said splice bars. 110

8. In a splice bar construction for rails the combination of a rail having a web with an opening therethrough, splice bars at opposite sides of the rail web having openings aligning with the opening of the rail web, a member extending through said aligning 115 openings of the splice bars and rail web, said member having transverse lugs on the outer ends thereof abutting against the outer surfaces of the splice bars, wedge means cooperating with said member in said openings for forcing the lugs into firm abutment with the outer sides of said splice bars, said lugs of the member having facing 120 surfaces tapered in an outwardly diverging relation.

9. In a joint for connecting rail sections the combination of rail sections having 130

webs with openings therethrough, splice bars at opposite sides of the rail web having openings aligning with the openings of the rail web, a wedge member extending through the series of aligning openings having transverse lugs at the ends thereof abutting with the outer surfaces of the splice bars, and a wedge key forced through said aligning openings into engagement with the wedge member to force the latter into a splice bar securing relation, the wedge key having a flexible end which may be bent into securing relation over an outer side of one of the lugs of said wedge member to maintain the key in position.

10. In combination with rail sections having webs with transverse openings therethrough, splice bars at opposite sides of the webs of the rail sections having openings aligning with the openings of the rail section webs, and complementary wedge parts through each series of aligning openings of the splice bars and webs, said complementary wedge parts at the sections thereof extending through the openings of the rail webs and being reduced and loosely fitting in the openings of said rail webs, and the portions of said complementary wedge parts which fit in said splice bars having a snug non-rotatable engagement therein, one of said complementary wedge parts having means at the outer sides of said splice bars for engagement on the splice bars to hold them clamped firmly together against the webs of the rails.

11. As an article of manufacture a wedge device for holding splice bars on rails consisting of a wedge body having transversely extending splice bar abutting lugs at the ends thereof, and a complementary wedge key cooperative with the wedge body, said key and wedge body having engageable

surfaces sloping in acute angled relation with respect to the longitudinal axis of the wedge device.

12. As an article of manufacture a wedge device for holding splice bars on rails consisting of a wedge body having transversely extending splice bar abutting lugs at the ends thereof, a complementary wedge key 50 cooperative with the wedge body, said key and wedge body having engageable surfaces sloping in acute angled relation with respect to the longitudinal axis of the wedge device, one of said lugs having a rounded 55 convex top surface.

13. As an article of manufacture a wedge device for holding splice bars on rails consisting of a wedge body having transversely extending splice bar abutting lugs at the 60 ends thereof, a complementary wedge key cooperative with the wedge body, said key and wedge body having engageable surfaces sloping in acute angled relation with respect to the longitudinal axis of the wedge 65 device, one of said lugs having a rounded convex top surface, said wedge parts at the intermediate cross section thereof being of cylindrical formation, and between the intermediate section and said lugs having 70 cross sections with at least one flat side.

14. In a wedge construction of the class described the combination of complementary wedge parts, one of the parts having transversely extending lugs at the ends 75 thereof, the other part being longer than the part upon which said lugs are formed and having an end which may be flexibly bent upwardly into engagement at the outer side of one of said lugs.
